(57) **CLAIM**

The ornamental design for a fabric sweeper, as shown and described.

DESCRIPTION

FIG. 1 is an isometric view of a fabric sweeper, embodying a new design, viewed from above, in front of, and from the right side of the fabric sweeper;

FIG. 2 is a front view of the fabric sweeper of FIG. 1;
FIG. 3 is a side plan view of the fabric sweeper of FIG. 1;
FIG. 4 is a bottom plan view of the fabric sweeper of FIG. 1;
and,

FIG. 5 is a top plan view of the fabric sweeper of FIG. 1.
The broken lines shown in the drawings are for illustrative purposes only and form no part of the claimed design. The fabric sweeper device is symmetric such that the front and back are identical, and the opposing sides are identical as well.
